US0D1103664S

(12) United States Design Patent (10) Patent No.: US D1,103,664 S
(45) Date of Patent: * Dec. 2, 2025

(54) SHOWCASE

(71) Applicant: LG DISPLAY CO., LTD., Seoul (KR)

(72) Inventors: Seokjin Im, Paju-si (KR); Jeongeon Seong, Paju-si (KR); Seokhyo Cho, Paju-si (KR); Hyunjung Song, Paju-si (KR); Soonmin Kwon, Paju-si (KR); Kihyoung Kim, Paju-si (KR)

(73) Assignee: LG DISPLAY CO., LTD., Seoul (KR)

() Term: 15 Years

(21) Appl. No.: 29/823,880

(22) Filed: Jan. 20, 2022

(30) Foreign Application Priority Data

Jul. 21, 2021 (KR) 30-2021-0034686

(51) LOC (15) Cl. 06-04

(52) U.S. Cl.

USPC D6/675.1

(57) CLAIM

The ornamental design for a showcase as shown and described.

DESCRIPTION

FIG. 1 is a front, right, top perspective view of the showcase showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the showcase that form no part of the claimed design.

1 Claim, 7 Drawing Sheets
